VALVE COMPENSATOR

Harold D. Church, Cleveland Heights, Ohio, assignor to The White Motor Company, Cleveland, Ohio, a corporation of Ohio

Application February 3, 1930, Serial No. 425,436

6 Claims. (Cl. 123—90)

This invention relates to compensating devices, and more particularly to means for compensating for expansion and contraction in the valve mechanism of an internal combustion engine.

5 One object of the invention is to provide a device of the character set forth in which the variable clearance normally present between a valve tappet and its associated valve stem or push rod is taken up by a body of liquid, the volume of 10 which is automatically varied to compensate for expansion or contraction of the parts.

Another object is to provide a device of this type in which the relative movement between the parts due to compression and leakage of the 15 liquid is reduced to a minimum.

A further object is to provide means to establish communication between the body of liquid in the valve and a source of supply each time the engine valve is seated.

20 Another object is to provide an improved arrangement for positively controlling a compensating device of this character.

Other objects relating to details of construction and economies of manufacture will appear 25 hereinafter.

In the accompanying drawings;

Fig. 1 is a vertical section through a cylinder of an internal combustion engine, illustrating the application of this invention;

30 Fig. 2 is a horizontal section of the engine illustrated in Figure 1 taken substantially on the line 2—2 of Fig. 3 with portions of the crank case broken away to show the liquid supply ducts;

Fig. 3 is a section taken substantially on the 35 line 3—3 of Fig. 2, the guide member being shown in elevation; and

Fig. 4 is a section taken on the line 4—4 of Fig. 3.

Referring to the drawings, the numeral 10 represents the cylinder block of an internal combustion engine of the overhead valve type. Each of the engine valves 11 co-operates with a seat 12 formed in the head 13, and is provided with a stem 14 extending upwardly through the head.

45 Valve springs 15 surround the stem and serve to press the valve firmly against its seat. A rocker arm 16, actuated by a push rod 17, is pivotally mounted on the head and operates to depress the valve stem 14 and thereby open the valve.

50 A cam shaft 18 is journalled in the crankcase 19 and is driven at one-half crankshaft speed in the conventional manner. A cam 20 is arranged on the cam shaft 18 in line with each push rod 17.

55 Guides 21 extend through apertures in the crankcase immediately above the cams, and are

formed with flanges 22 resting upon the crankcase. The two guides for each cylinder are secured in position by means of a bolt 23 engaging the adjacent edges of the flanges 22. A cover plate 24 extends from the crankcase 19 to the head 13 and conceals and protects the push rods 17 and the guides 21.

Each guide 21 is formed with a cylindrical bore extending therethrough and having an annular enlargement 25 below the flange 22. A port 26 extends through the wall of the guide 21 opens into the enlargement 25 and communicates with a duct 27 in the wall of the crankcase.

Slidably mounted in each guide is a sleeve 28 having, near its lower end, an internal boss 29 formed with a restricted axial bore 30. A valve 31 seats on the upper surface of the boss 29 and has its stem 35 extending through the bore 30. A lateral bore 32 communicates with the enlargement 25 and opens below the seat of the valve 31. At its lower end, the sleeve 28 is provided with a counter-bored enlargement 33 carrying a bearing plate 34 which rides on the cam 20. The lower end of the valve stem 35 projects through the enlargement 33 and the plate 34.

Slidable within the sleeve 28 is a tappet 36 having recesses 37 and 38 in its opposite ends. The recess 37 receives a spring 39 which surrounds the upper end of the stem of the valve 31 and bears on the valve 31 and the tappet. The recess 38 receives a member 40 which is provided with a socket to receive the ball head 41 of the push rod 17.

The cam 20 is formed with a centrally disposed annular groove 42 which is eccentric or cam 85 shaped with respect to the shaft 18 and which receives the projecting end 35 of the valve stem. The face of the groove 42 is arranged with its high portion represented by the arc A in Fig. 4, opposite the high portion of the cam 20, represented by the arc B, so that the valve 31 is opened when the engine valve 11 is closed, and vice versa.

In operation, oil or other liquid under pressure is admitted to the ducts 27 through the duct 43 from any suitable source, such as the pressure 45 lubricating system of the engine. The oil passes through the ducts 26 and 32 and is allowed to fill the space between the boss 29 and the end of the tappet 36, and also the recess 37. When the engine is operating, the cam 20 raises the sleeve 28 once in each revolution of the cam shaft. The thrust on the sleeve is transmitted to the tappet 36 through the oil confined between the sleeve and the tappet, and to the valve 11 through the push rod 17, and the rocker arm 16. During 55

this operation, the valve 31 is held closed by the spring 39 and the pressure of the oil, the projecting end of the valve stem 35 passing through the low portion of the groove 42.

5 After the cam 20 has passed its high point, the valve springs 15 return the valve 11 to its closed position. Shortly thereafter, the high portion of the cam groove 42 engages the valve stem 35 and forces the valve 31 upwardly from its seat against the pressure of the spring 39. Oil is thereby allowed to enter or leave the space between the sleeve 28 and the tappet 36 to compensate for any variation in length of the push rod or associated parts, and maintain a minimum clearance throughout the entire valve mechanism. During this cycle, the spring 39 keeps the sleeve 28 and the tappet 36 pressed apart, so that all the clearance in the train appears between these two members.

20 It will be evident that the quantity of oil under compression when the cam 20 opens the engine valve 11 is relatively small, thereby minimizing the undesirable effects arising from the relatively high compressibility of oil. In order to maintain the body of oil under compression as small as possible, the clearance between the sleeve 28 and the tappet 36 is not substantially greater than the clearance ordinarily used between the parts of a conventional valve mechanism to permit expansion. This arrangement has the additional advantage of allowing the valve to function in the normal manner even if the supply of oil should fail.

Under normal conditions, the engine is frequently started when cold. As the temperature rises the various metallic elements expand. The expansion of the valve mechanism is compensated by a gradual decrease in the quantity of oil between the sleeve 28 and the tappet 36, an increment of the oil contained between these members being expelled at each opening of the valve 31. It is evident that the engine valve 11 is allowed to seat perfectly at all times, although the oil valve 31 does not open until after the seating of the engine valve, since the extremely small amount which the valve mechanism may expand during one revolution of the cam shaft is readily absorbed by compression of the oil.

50 Although the invention has been described as applied to an overhead valve internal combustion engine, it will of course be understood that the compensating device may be applied to any other type of engine or machine in which it is desired to maintain a minimum clearance between parts of variable length. It is also to be understood that the specific terminology employed is not to be construed as restrictive or limiting, and that various modifications and re-arrangements of parts may be resorted to without departing from the scope and spirit of the invention as defined in the following claims.

I claim:

1. A self-adjusting valve mechanism comprising a pair of cams, an engine valve spring-pressed to closed position, a bearing member for engaging one of said cams and receiving the thrust thereof, a tappet spaced from said bearing mem-

ber for transmitting thrust to said valve, a spring normally maintaining said bearing member and said tappet in spaced relation, a body of liquid for transmitting thrust from said bearing member to said tappet, and a valve for said liquid controlled by the other of said cams.

5 2. In an internal combustion engine, a self-adjusting valve mechanism including a cam having an eccentric groove therein, a bearing member for engaging said cam, and a valve in said bearing member having its stem positioned in said groove.

3. In a self-adjusting valve operating mechanism, a shaft, a cam on said shaft having a groove in the face thereof eccentric with respect to said shaft, a bearing member for engaging said cam, and a valve in said bearing member having a stem projecting therethrough and co-operating with said groove.

20 4. In a mechanism for valves, an annular member and movable closure forming a fluid chamber and a passage leading thereto from a fluid port associated with a source of fluid supply, a valve spring-returned to its seat, and separating such passage and chamber, and having an operating 25 tip and cams associated with said annular member and said operating tip.

5. In a self-adjusting valve lifter for internal combustion engines having a spring-pressed engine valve, a valve stem and a cam shaft, a fixed 30 casing, a hollow member mounted for reciprocation in the casing and having a fluid column therein, a plunger adapted to rest on the fluid column in the hollow reciprocating member between said member and the engine valve stem, a 35 slideable valve also in the hollow reciprocating member for making and breaking the fluid column, said slideable valve having a stem which protrudes from the reciprocating member, and a cam on the cam shaft having an arcuate depression 40 therein with which the said slideable valve stem is adapted to register once every revolution of the cam, said cam being arranged to move the hollow reciprocating member within the casing.

6. In combination, a camshaft having a cam 45 thereon, a spring closed engine valve, means for receiving and transmitting the thrust of said cam to said valve including a pair of aligned members spaced apart to form a chamber therebetween, a body of liquid in such chamber, said members being mounted to serve as a unit in transmitting the thrust of said cam and to move relative to one another to adjust the length of said means, a passage formed in one of said members connecting said chamber with a 50 source of liquid supply, a control valve arranged to close said passage and mounted to be moved towards closed position by the pressure exerted on the body of liquid in said chamber by the thrust of said cam, a spring pressing said valve 55 towards a closed position, and a second cam on said cam shaft arranged for engagement with said control valve and designed to open said control valve at predetermined intervals in the rotation of said camshaft.

65 HAROLD D. CHURCH.
